(57) **CLAIM**

The ornamental design for a propulsion control system for ship with a display, as shown and described.

DESCRIPTION

FIG. 1 is a perspective view of a propulsion control system for ship with a display showing my new design;

FIG. 2 is a rear elevational view thereof;

FIG. 3 is a front elevational view thereof;

FIG. 4 is a top plan view thereof;

FIG. 5 is a right side view thereof;

FIG. 6 is a left side view thereof; and,

FIG. 7 is a perspective view thereof with the top portion rotated 180°.

The broken line showing is for the purpose of illustrating portions of the propulsion control system for a ship with a display which form no part of the claimed design.
